ATTORNEY

UNITED STATES PATENT OFFICE.

BRUCE FORD, OF PHILADELPHIA, PENNSYLVANIA.

SECONDARY OR STORAGE BATTERY.

1,233,754.

Specification of Letters Patent. Patented Sept. 4, 1917.

Application filed February 8, 1915. Serial No. 5,827.

To all whom it may concern:

Be it known that I, BRUCE FORD, a citizen of the United States, and a resident of Philadelphia, in the county of Philadelphia and State of Pennsylvania, have invented certain new and useful Improvements in Secondary or Storage Batteries, of which the following is a specification.

The principal objects of the present invention are first, to provide for steadyng, or preventing lateral shifting of, plates in respect to their container without increasing the hazard of short-circuiting by sediment, and second, to provide improved storage batteries for portable, vehicle, submarine and like uses.

The invention will be claimed following a description of the invention which will be given in connection with the accompanying drawings, in which

Fig. 1, is a side view, principally in section.

Fig. 2, is a similar view with parts broken away illustrating a modification.

Fig. 3, is a similar view illustrating another modification, and

Fig. 4, is a detail view of Fig. 2, showing an additional modification.

In the drawings, referring more particularly to Fig. 2, 1 is a jar or container, as of hard rubber, having a rib 2 upstanding from its bottom and forming sediment space 3. 4, are plates of one polarity having feet 5 arranged to abut on one face of the rib 2. 6 are plates of the other polarity having feet 7 arranged to abut on the other face of the rib 2. These feet coöperating with the rib obviously steady the plates.

The capacity for sediment is limited by the distance between the bottom edge of the plates and the bottom of the container and sediment may rise almost to the bottom of the plates without bridging plates of unlike polarity and thus causing short-circuits, since the feet on one side of the rib 2 are of one polarity and the feet on the other side of the rib 2 are of the other polarity they may become embedded in sediment which will not produce short-circuiting.

As shown in Fig. 1, the jar 1 is provided with a pair of spaced upstanding ribs 2 and the feet 5^a on the plates of one polarity engage with the outer face of one rib while the feet 7^a of the plates of the other polarity engage with the outer face of the other rib.

The plates of each polarity being thus held at their bottoms against shifting in only one direction, they may be prevented from shifting in the opposite direction by the straps 9 and 10 at their tops engaging the side walls of the container. The operation is as has been above described and the arrangement is well adapted for comparatively wide and low plates.

As shown in Fig. 3 each plate has two feet. The feet 5^b of plates of one polarity coöperate with the adjacent faces of the ribs 2^b and the feet 7^b of plates of the opposite polarity coöperate with the distant faces of the ribs 2^b. The tops of the plates may be held against shifting by providing a snug fit between the terminal posts 11 and 12 and the cover 13. The mode of operation is as has been above described and the arrangement is well adapted for narrow and high plates. If the jar is not of insulating material or lined with insulating material, insulating caps 8 may be applied to the feet as shown in Fig. 4.

14 is one of the separators interposed between the plates and which extends beyond the sides of the plates, which are narrower than the jar and the separator, so as to fit between the sides of the jar. In this way 85 the separator is held against lateral shifting and since the plates are also held against lateral shifting it follows that the projecting marginal portions of the separators operate to prevent short-circuiting 90 between plates of unlike polarity which might occur if the edges of the plates and separators were in alinement. Moreover the bottom of the jar being ribbed forms 95 separated sediment spaces; the point being that the projections from plates of unlike polarity must not extend into the same sediment space, as the sediment rising to the projections would cause a short-circuit before the entire sediment space had been 100 utilized.

It will be obvious that modifications may be made in details without departing from the spirit of the invention, which is not limited as to such matters.

What I claim is:

1. In a storage battery the combination of a container provided with a rib upstanding from its bottom, and plates provided with projections extending from their bottoms and of which those appertaining to plates of one sign engage one face only of

the rib and those appertaining to plates of the other sign engage the other face only of the rib, substantially as described.

2. In a storage battery the combination of 5 a container provided with a rib upstanding from its bottom, plates narrower than the container and provided with projections extending from their bottoms and of which those appertaining to plates of one polarity engage one face of the rib and those appertaining to plates of the other polarity engage the other face of the rib, and separators wider than the plates and extending beyond the same.

3. In a storage battery the combination of 15 a container having a ribbed bottom providing separate sediment spaces, and plates of different polarity provided with projections engaging the ribbed portion of the container, the projections of unlike polarity being in different sediment spaces. 20

In testimony whereof I have hereunto signed my name.

BRUCE FORD.
